US0D1001831S

(12) **United States Design Patent** (10) **Patent No.:** **US D1,001,831 S**
Thoren et al. (45) **Date of Patent:** **** Oct. 17, 2023**

(54) **DISPLAY SCREEN WITH GRAPHICAL USER INTERFACE FOR AN HVAC CONTROL DEVICE**

(71) Applicant: **Daikin Manufacturing Company, L.P.**, Waller, TX (US)

(72) Inventors: **Dennis Thoren**, Lindale, TX (US); **Tao Jia**, Mooresville, NC (US); **Jacky Chen**, Katy, TX (US); **Hugh Dubberly**, San Francisco, CA (US)

(73) Assignee: **Daikin Manufacturing Company, L.P.**, Waller, TX (US)

(**) Term: **15 Years**

(21) Appl. No.: **29/719,102**

(22) Filed: **Dec. 31, 2019**

(51) **LOC (14) Cl.** **14-04**

(57) **CLAIM**

The ornamental design for a Display Screen with Graphical User Interface for an HVAC Control Device, as shown and described.

DESCRIPTION

The sole FIGURE is a front view of a display screen with graphical user interface for an HVAC control device.

The dashed broken lines showing portions of the graphical user interface, the outline of the HVAC control device, the control portion of the HVAC control device, and the surrounding environment of the HVAC control device are for the purpose of illustrating environmental structure and forms no part of the claimed design.

1 Claim, 1 Drawing Sheet
